UNITED STATES PATENT OFFICE

ROBERT K. CLARK, OF SPRINGFIELD, MASSACHUSETTS, ASSIGNOR TO THE AMERICAN THREAD COMPANY, OF NEW YORK, N. Y., A CORPORATION OF NEW JERSEY

SEWING-MACHINE BOBBIN

Application filed January 12, 1929. Serial No. 332,119.

My invention relates to improvements in sewing machine bobbins and has for its object to provide a bobbin having permanently secured hereto a resilient member whose edges 5 contact with the surface of the cavity of the shuttle so as to produce a friction or drag preventing the bobbin from "throwing" when used in the sewing machine. The bobbin is preferably provided with two end thread 10 contacting disks or flanges, one of which lies within the friction device and preferably there is a friction device upon one end only of the bobbin. In the preferred form the thread mass is wound upon a tubular core, 15 one end of which is crimped so as to secure one thread contacting disk and a superimposed friction member, while the other end is crimped so as to secure the contacting disk at the other end of the bobbin.

20 The following is a description of an embodiment of my invention reference being had to the accompanying drawing, in which:

Figure 1 shows partly in section and partly in side elevation a bobbin embodying my 25 invention in its preferred form;

Fig. 2 is an upper plan view of the same.

Referring more particularly to the drawings, 2 is a cylindrical core of cardboard or other suitable material having wound there- 30 on a mass of thread 4 so as to form a cop, the winding being of the well known universal type so as to be self-supporting. 6-6 are end pieces having central perforations through which the ends of the core pass and 35 inturned edges 8-8 which are yieldingly held against the peripheries of the ends of the mass 4. 10 is a centrally perforated friction disk, being a saucer-shaped member pressed up from sized paper or other suitable ma- 40 terial and given a positive set, the same being resilient so as to tend to return to the shape shown in Fig. 1, when its periphery is moved toward the thread mass 4. This periphery 12 is circular and when the bobbin is within 45 the shuttle chamber, bears against one end of the chamber with a spring pressure so as to produce a drag upon the bobbin preventing its "throwing" when the machine is in operation. The end 14 of the core passes 50 through the lower disk 8 and is crimped over

so as to hold that disk in place, while the end 16 passes through the upper disk 8 and the member 10 and is crimped so as to hold both those two members in place. The upper disk 8 is provided with a central depression into 55 which the central portion of the member 10 extends. The plane of the edge 12 is located a considerable distance beyond the crimped end 16 of the core and for some distance from its periphery it is spaced away from the 60 thread mass 4 and the adjacent disk 8 so as to be unsupported. The intermediate portion of the upper disk 8 contacts with the intermediate portion of the member 10 and assists in the return of the member 10 to its original 65 position after the edge 12 has been pressed toward the thread mass 4.

As will be evident to those skilled in the art my invention permits various modifications without departing from the spirit 70 thereof or the scope of the appended claims.

What I claim is:

1. A sewing machine bobbin comprising a core, a mass of thread wound thereon into cop form, a resilient disk secured to one end 75 of said core and having its edge located in a plane beyond the end of said core, the rear side of said disk being unsupported for a considerable distance from its periphery.

2. A sewing machine bobbin comprising a 80 core, a mass of thread wound thereon into cop form, a resilient disk secured to one end of said core and having its edge located in a plane beyond the end of said core, the rear side of said disk being unsupported for a 85 considerable distance from its periphery, said disk being normally saucer-shaped.

3. A sewing machine bobbin comprising a core, a mass of thread wound thereon into cop form, a resilient disk secured to one end of 90 said core and having its edge located in a plane beyond the end of said core, the rear side of said disk being unsupported for a considerable distance from its periphery, and two disks having inturned edges engaging 95 the ends of said thread mass, one of said engaging disks lying between said resilient disk and said mass.

4. A sewing machine bobbin comprising a core, a mass of thread wound thereon into cop 100

form, a resilient disk secured to one end of said core and having its edge located in a plane beyond the end of said core, the rear side of said disk being unsupported for a considerable distance from its periphery, and two disks having inturned edges engaging the ends of said thread mass, one of said engaging disks lying between said resilient disk and said mass, and having a reentrant central portion into which said resilient disk extends.

5. A sewing machine bobbin comprising a core, a mass of thread wound thereon into cop form, a resilient disk secured to one end of said core and having its edge located in a plane beyond the end of said core, the rear side of said disk being unsupported for a considerable distance from its periphery, and two disks having inturned edges engaging 10 the ends of said thread mass, one of said engaging disks lying between said resilient disk and said mass, and having a reentrant central portion into which said resilient disk extends.

15. A sewing machine bobbin comprising a core, a mass of thread wound thereon into cop form, a resilient disk secured to one end of said core and having its edge located in a plane beyond the end of said core, the rear side of said disk being unsupported for a considerable distance from its periphery, and two disks having inturned edges engaging 20 the ends of said thread mass, one of said engaging disks lying between said resilient disk and said mass, the ends of said core being crimped so as to hold said three disks.

25. A sewing machine bobbin comprising a core, a mass of thread wound thereon into cop form, disks engaging the ends of the thread mass and held against the thread mass by crimping of the outer ends of the core, said core and disk being made of paper, and a 30 saucer-shaped disk secured between one of the first mentioned disks and the adjacent crimped end of the core, said saucer-shaped disk being made of paper of the requisite resiliency so that when the bobbin is in operation 35 in the shuttle it produces a friction or drag to prevent the bobbin from overrunning.

In testimony whereof, I have signed my name to this specification this 3rd day of January, 1929.

ROBERT K. CLARK.
